UNITED STATES PATENT OFFICE

161,669

PORTABLE DEVICE FOR VAPORIZING
STERILIZING SOLUTIONS

Phillip W. Zonne, Los Angeles, Calif., assignor to
American Electronic Mfg. Inc., Los Angeles,
Calif., a corporation of California

Application June 27, 1949, Serial No. 3,564

Term of patent 7 years

(Cl. D83—1)

To all whom it may concern:

Be it known that I, Phillip W. Zonne, a citizen of the United States and a resident of Los Angeles, California, have invented a new, original, and ornamental Design for a Portable Device for Vaporizing Sterilizing Solutions, of which the following is a specification, reference being had to the accompanying drawing, forming part thereof.

Referring to the drawing:

Figure 1 is a front elevation of a portable device for vaporizing sterilizing solutions, showing my new design;

Figure 2 is a side elevation of the device as viewed from the left of Figure 1; and

Figure 3 is a top plan view of the device.

I claim:

The ornamental design for a portable device for vaporizing sterilizing solutions, as shown.

PHILLIP W. ZONNE.
